UNITED STATES PATENT OFFICE.

THOMAS W. HARVEY, OF HUNTINGTON, WEST VIRGINIA.

GARMENT RACK.

1,409,852.

Specification of Letters Patent.

Patented Mar. 14, 1922.

Application filed June 29, 1920. Serial No. 392,756.

To all whom it may concern:

Be it known that I, THOMAS W. HARVEY, a citizen of the United States, residing at Huntington, in the county of Cabell and 5 State of West Virginia, have invented new and useful Improvements in Garment Racks, of which the following is a specification.

This invention relates to a rack or tree which may be properly termed a night rack 10 intended to support articles of apparel in convenient and orderly arrangement when removed from a person at night preparatory to retiring and disposed in readily accessible association for subsequent wearing application. The improved rack has been devised particularly for use in bedrooms and is provided with means for hanging and maintaining articles of wearing apparel thereon in such manner that the desirable shape of the 15 apparel will be preserved. Among other of the many advantages of the rack is a provision for hanging or suspending trousers from the waist band portion in order to overcome the necessity for manually removing 20 and also preventing accidental displacement or falling out of the contents of the pockets and at the same time hold the trousers in a position to preserve the desirable shape thereof. The improved rack also embodies 25 means for hanging a coat and vest in a shapely manner as well as other articles of wearing apparel. The improved rack is readily portable or may be easily moved from one place to another, and it is proposed 30 to construct the same either of wood or metal.

The preferred form of the improved rack is shown in the accompanying drawings, wherein:—

Fig. 1 is a perspective view of the improved rack formed of suitable wood.

Fig. 2 is a top plan view of the upper extremity of the rack shown by Fig. 1.

Fig. 3 is a side elevation of the upper extremity of the rack as shown by Fig. 1 and 45 illustrating a portion of the main standard broken away.

Fig. 4 is a perspective view of the improved rack shown made of metal.

Fig. 5 is a top plan view of the upper extremity of the rack shown by Fig. 4, parts 50 being illustrated in horizontal section.

Referring to Figs. 1, 2 and 3, the numeral 5 designates a central standard or upright having divergent legs 6 secured to the lower 55 extremity thereof to provide a stable support therefor. On the upper end of the standard

or upright 5 is a cross-arm 7 having a bowed hanger and garment shaper 8 fixed to one end thereof and adapted to receive a coat and vest or analogous garments. At the opposite end of the arm 7 an elongated resilient clamp or holder 9 is secured, said clamp or holder consisting of a pair of spring jaws 10 preferably formed by doubling a spring metal bar or rod and slightly flaring the free 60 ends 11 to provide for ready insertion and withdrawal of a garment relatively to the jaws. As shown by Fig. 2 the clamp or holder 9 is extended equally on opposite sides of the end of the arm 7 and one jaw is centrally secured as at 12 to the end of the said arm. For clearance purposes the arm 7 is formed with lower bevels 13 to remove the material so as to give the said arm at its ends a reduced construction to avoid interference with 65 or bearing upon the garments applied to the devices 8 and 9. At the center of the top of the arm 7 a ring or other analogous gripping device 14 is secured to facilitate carrying or moving the rack as a whole from one place 70 to another. At a suitable distance below the arm 7 upwardly inclined pins 15 project outwardly from the standard or upright 5 and terminate in suitable heads or balls 16, these pins 15 being adapted to support a shirt, collar, necktie, undergarments, etc. The standard or upright 5 also has oppositely disposed 75 upwardly inclined hanger arms 17 projecting therefrom at a suitable elevation above the lower supported extremity of the said 80 standard or upright, and from the ends of the said hanger arms flexible hanger devices 18 depend and are intermediately secured to shoe shapers or formers 19. Below the arms 17 a hanger pin 20 also projects outwardly 85 from the standard or upright 5 and terminates in a head 21, the said pin 20 being adapted to support socks or stockings. The parts of the improved rack thus far described are preferably formed of wood, except the clamp or holder 9, the flexible hanger devices 18 and ring or gripping device 14, and will be of a comparatively light 90 weight.

Figs. 4 and 5 show the improved rack 105 formed of metal, the standard or upright 22 in this instance being formed of a suitable metal tube having divergent legs 23 secured to the lower end thereof by a collar or socket 24. The upper cross-arm 25 is secured to the 110 upper end of the standard or upright 22 by a T-union 26 having end caps 27, a garment

holder and shaper 28 being secured to one cap and a clamp or holder 29 centrally connected to the opposite cap, as clearly indicated by Fig. 5. To the center of the top portion of the T-union 26 a suitable ring or analogous device 30 is secured for carrying this form of the rack from one place to another, and below the arm 25 are outwardly projecting upwardly inclined pins 31. This form of the rack also has lower hanger arms 32 with flexible depending hanger devices 33 attached thereto and also secured to shoe formers 34. Below the arms 32 a hanger pin 35 extends outwardly from the standard or upright 22. This metal form of the improved rack embodies precisely the same features as that shown by Figs. 2 and 3, the only difference being in the construction in order to adapt the several parts to the metal components above described.

It will be understood that both forms of the rack may be suitably ornamented or tastefully decorated and also may be modified in the general proportions and dimensions as may be desired and found necessary.

In the use of the improved rack a coat and vest when removed from the person are applied over the holder and shaper 28 and the trousers are suitably folded at the waist band portion and drawn inwardly between the jaws 10 of the holder 9 and securely held with the legs depending and the pockets and the contents thereof in normal condition, and whereby the trousers will be preserved in shape and the necessity of removing the contents of the pockets avoided. The shoes may be readily applied to the formers 19 or 34 and held suspended and in proper shape from the arms 17 or 32, and the socks or stockings may be hung over the pin 20 or 35. A collar, necktie, shirt and undergarments may be readily arranged and supported upon the upper pins 15 or 31, and by this means all of the apparel of a person may be conveniently grouped or associated for ready reapplication to the wearer. It will be seen that the garments are held separated by the several devices of the improved rack adapted to hold the same, and, as a consequence, there will be no interference or crowding of the garments which will remain in orderly arrangement for easy removal. The improved rack will also be found advantageous in overcoming the inconveniences heretofore frequently experienced in bedroom disposal of garments, and particularly in hanging trousers in such manner that their shape will be preserved without reversing the same, as ordinarily practiced, and necessitating the removal of the contents of the pockets. Numerous other advantages will become apparent to users of the improved rack, and in view of the simplicity of the several parts it may be readily manufactured and assembled at a comparatively small cost.

What is claimed as new is:

1. A garment rack of the class specified, consisting of a rigid standard, a cross arm immovably secured at its central portion on the upper end of the standard, a coat hanger and shaper immovably fixed at its intermediate portion to one end of the cross arm, and a holder for trousers immovably fixed at its intermediate portion to the opposite end of said cross arm, the trousers holder comprising a pair of elongated spring jaws open and accessible at one end only and adapted to hold trousers by the waistband portion of the latter to obviate displacement of the contents of the pockets of the trousers, the trousers holder having only the inner member thereof secured to the end of the cross arm and the outer member free to move outwardly from and inwardly towards the said inner member.

2. A garment rack of the class specified, comprising a rigid standard having a supporting means at its lower end, a cross arm immovably fixed at its central portion to the upper end of the standard, and coat and trousers holding means individually and immovably fixed at their intermediate portions to opposite ends of the cross arm in planes at right angles to the latter and held by said cross arm at a distance from the standard, the trousers holder consisting of a pair of straight jaws which are normally parallel and open and accessible at one end only and adapted to hold trousers by the waistband portion of the latter to obviate displacement of the contents of the pockets of the trousers, the trousers having the inner member only thereof secured to the cross arm.

3. A garment rack of the class specified, comprising a rigid standard having supporting means at its lower end, a cross arm immovably fixed at its central portion on the upper end of the standard and provided with rigidly secured coat and trousers holding means at the opposite ends and at right angles thereto, and outwardly projecting devices disposed in spaced relation along the length of the standard at various vertical elevations for holding articles of clothing thereon, a portion of said projecting devices being provided with depending flexible hangers secured to intermediate portions of shoe engaging means, a single outwardly projecting device being located between the outwardly projecting devices having the depending flexible means secured to the shoe engaging means and the lower supporting means for the standard for holding foot apparel.

4. A garment rack of the class specified, comprising a standard, a cross arm immovably fixed on the upper end of the standard and projecting outwardly equally beyond opposite sides of said standard, a garment supporting means fixed on one end of the

said arm, and a trousers holder intermediately secured against the remaining end of the cross arm and consisting of a pair of elongated longitudinally straight jaws open 5 at one end only, the inner member of the trousers holder being secured to the cross arm and the outer member free to move outwardly from and inwardly towards the inner secured member for receiving and tightly 10 holding the waistband portion of trousers.

5. A garment rack of the class specified, comprising a standard, a cross arm immovably fixed on the upper end of the standard and projecting outwardly equally beyond 15 opposite sides of the latter, a coat hanger and shaper intermediately secured against movement on one end of the cross arm and having a bowed shape and disposed at right angles to the cross arm, and a trousers holder

intermediately secured against the opposite 20 end of the cross arm and consisting of a pair of longitudinally straight elongated jaws, the inner jaw being centrally fixed to the end of the cross arm to dispose the trousers holder at right angles to the arm and 25 both jaws open at one end only, the outer jaw of the trousers holder being free to move outwardly from and inwardly towards the inner secured jaw to receive and positively hold the waistband portion of trousers.

30 In testimony whereof I have hereunto set my hand in presence of two subscribing witnesses.
